UNITED STATES PATENT OFFICE.

EDWARD L. SIBLEY, OF BENNINGTON, VERMONT.

PAPER-CLIP.

SPECIFICATION forming part of Letters Patent No. 752,185, dated February 16, 1904.

Application filed April 13, 1903. Serial No. 152,377. (No model.)

To all whom it may concern:

Be it known that I, EDWARD L. SIBLEY, a citizen of the United States, residing at Bennington, in the county of Bennington and State 5 of Vermont, have invented a certain new and useful Improvement in Paper-Clips, of which the following is a full, clear, and exact description.

This invention relates to that class of spring 10 devices used for temporarily connecting sheets of paper, fabric, and other objects and variously known as "paper-clips" or "paper-fas-teners."

The object of the invention is the produc- 15 tion of an efficient metal paper-clip without waste of metal or with a small waste.

The invention consists of a many-armed metal piece bent upon itself to bring its arms in opposition and whereby the elasticity of the 20 metal is utilized to grip between the arms the object or objects to which the clip is applied, the arms being offset from a transverse connecting member, all as I will proceed now more particularly to set forth and claim.

25 In the accompanying drawings, illustrating the invention, in the several figures of which like parts are similarly designated, Figure 1 is a plan view showing one method of forming the blanks without waste. Fig. 2 is a plan 30 view of one of the blanks of Fig. 1, and Fig. 3 is a perspective view of the finished clip formed from the blank of Fig. 2. Fig. 4 is a plan view illustrating another method of forming the blanks without waste. Fig. 5 is a plan 35 view of the blank of Fig. 4, and Fig. 6 is a perspective view of the finished clip formed from the blank of Fig. 5.

40 Referring to Figs. 1 to 3 and also to Figs. 4 to 6, it will be seen that the devices are blanked out of a strip of metal, as shown in Figs. 1 and 4, without waste, alternate blanks being shown in black and white the more clearly to indicate the lines of cut. Spring metal, such as brass, is preferably used. In 45 these forms four arms are used, and in Figs. 1 to 3 the arms 1 and 2 are offset from a transverse connecting member 3, which extends obliquely of the arms, while in Figs. 4 to 6

the arms 4 and 5 are offset from a transverse connecting member 6, which extends at right 50 angles to the arms. The blank, Fig. 2, has its arms 1 bent over upon the arms 2, so that their ends lap over upon them, and this is possible by reason of the obliquity of the connecting member 3. The arms 2 therefore 55 form a base against which the arms 1 may grip an object. The blank of Fig. 5 has its arms 4 bent over arms 5, but because the connecting member 6 is at right angles to the arms the arms will alternate, and while parallel or in opposition they are not superposed, as in Fig. 3. If the blank of Fig. 5 be folded on a line running obliquely across the connecting member 6, then the clip will have over- 60lapping arms, as in Fig. 3. In all of the forms 65 of clip the folding is such as to leave more or less of a loop adjacent the connecting member, and the arms shown uppermost in Figs. 3 and 6 are bent toward the arms shown beneath in 70 said views, so that the clips may have the necessary resilience and gripping power, and the ends of the uppermost arms are reversely curved, so as to facilitate the application of 75 the clips to an object. A characteristic of all of these forms of clips is that their arms are parallel, or substantially so, in the plane where the actual gripping is effected.

While I have particularly shown and de- 80 scribed these various embodiments of my in- vention, I wish it to be understood that it is 80 susceptible of other variations.

What I claim is—

1. A paper-clip, composed of arms and a transverse connecting member arranged obliquely with relation to said arms. 85
2. A paper-clip, having offset arms and a transverse connecting member.
3. A paper-clip, having offset arms and a transverse connecting member arranged obliquely to said arms. 90
4. A paper-clip, having offset arms and a transverse connecting member arranged obliquely to said arms, said arms folded over and in contact at their gripping plane.
5. A paper-clip, composed of a piece of 95 metal folded upon itself, and having a number

of arms arranged to come in opposition and offset from and connected by a transverse member to form a spring, to grasp an object or objects placed between said arms.

5 6. A paper-clip, having offset arms and a transverse connecting member, the arms being folded over and overlapping.

In testimony whereof I have hereunto set my hand this 11th day of April, A. D. 1903.

EDWARD L. SIBLEY.
